UNITED STATES PATENT OFFICE.

FRANCIS SEYMOUR, OF PATERSON, NEW JERSEY.

MACHINE FOR DOUBLING, TWISTING, AND QUILLING.

1,146,027.

Specification of Letters Patent. Patented July 13, 1915.

Application filed May 27, 1911. Serial No. 629,762.

To all whom it may concern:

Be it known that I, FRANCIS SEYMOUR, a citizen of the United States, residing at Paterson, in the county of Passaic and State 5 of New Jersey, have invented certain new and useful Improvements in Machines for Doubling, Twisting, and Quilling, of which the following is a specification.

This invention relates to machines employed in those treatments on thread or 10 yarn, known as doubling, twisting and quilling.

The invention consists in certain improvements in these machines whereby quilling 15 alone, without doubling or twisting, or quilling with twisting (compound or single) or with doubling and twisting, may all be accomplished in one and the same machine; whereby the traverse may be regulated to 20 vary the pitch of the windings of the quill or other wound package; and whereby the diameter of the wound package may be varied as the circumstances affecting the connection in which it is to be used may require.

The invention further consists in several 25 other features involving improved constructions and arrangements of parts whereby to increase the output materially, improve the quality of the product and attain a higher 30 degree of efficiency in general, salient among which latter features may be mentioned those involving the spindle groups and the mechanism for stopping the operation with 35 respect to any particular thread should any irregularity attending the same arise.

The invention will be found fully illustrated in the accompanying drawings, wherein,

Figure 1 is an elevation of one side of 40 that end-portion of the machine at which the power is introduced, certain parts being removed; Fig. 2 is an elevation of the same side of the other end-portion of the machine, certain parts being removed; Fig. 3 is an 45 end elevation of what is shown in Fig. 1; Fig. 4 an end elevation of what is shown in Fig. 2; Fig. 5 is a horizontal sectional view taken just above the plane of the spindle-driving belt, certain parts being removed; 50 Fig. 6 is an enlarged detail view showing one of the spindle units and the means associated therewith for effecting the traverse

and the advance of the thread longitudinally of the winding axis in the building of the package, the means for causing the feed of 55 the thread or yarn to the receiving spindle, and the means for stopping the rotation of the spindle, the feeding of the thread and the traverse motion upon the breaking of a thread; Fig. 7 is an enlarged detail view, in 60 plan, of one of the spindle-rails, the spindle-driving belt, one of the pivoted spindle units and a part of the means controlling the movements of the latter; Fig. 8 is an enlarged detail view of a part of the means 65 for advancing the thread longitudinally of the axis of winding, as seen from the right of one of the spindle units in Fig. 1; Fig. 9 is a plan view of what is seen in Fig. 8; Fig. 10 is a plan view of a detail of Fig. 3, 70 on a somewhat smaller scale; and, Fig. 11 is a detail view illustrating the fallers for one of the spindle groups.

a designates a series of uprights all substantially the same in construction and secured together by the two spindle-rails *b*, two tubular braces *c* and other rails and shafts (some of which require no special mention and others of which will be hereafter referred to) so as to form the frame 80 of the machine.

In a plane somewhat above the spindle-rails *b* is disposed the continuous spindle-driving belt *d*. Referring to Fig. 5 it will be seen that this belt is so maintained as 85 to produce therefrom two loops *d'* *d''* one within and parallel with the other. At one end of the machine the loop *d'* extends around the large driving pulley *e*, and the loop *d''* around the two idlers *f*; at the other end of 90 the machine the loops of the belt are maintained by the idlers *g*, the parallelism between the two loops being maintained by the idlers *h*. The pulley *e* is carried by the vertical shaft *i* journaled in the brackets *j* and 95 *k*, while the idlers *f* are carried by the bracket *l* and the idlers *g* are carried by a bracket *m* movable toward and from the pulley *e* and idlers *f*, being supported on fixed studs *n* projecting from the adjacent 100 end upright *a* and normally forced from said upright by a lever *o* fulcrumed in a bracket *p*, bearing at its upper end against the bracket *m* and subjected to the pull of

a spring *q* which connects its lower end with a stem *r* adjustably secured in the next adjoining upright *a* (Figs. 2 and 5).

s designates fast and loose pulleys on the shaft *i* around either of which the driving belt (shown in broken lines in Fig. 1) is passed, said driving belt being adapted to extend around a pulley *t* journaled in a stand *u* projecting up from one of the brackets *j'* and also around a pulley *v* journaled in a stand *w* which is vertically movable in the other bracket *j'* and may be shifted vertically, to shift the belt from the one to the other of the pulleys *s*, by manipulating a lever *x* operatively connected with said stand and provided with a pin *y* to be entered into holes *z* in the lever *x* and bracket *j'* to hold the former at the position to which it is adjusted. The stands *u* and *w* are so constructed that their positions in the brackets *j'* may be interchanged to adapt them to the belt whether it is running one way or the other.

At suitable intervals tubular posts 2 are pivoted on the stems 3 secured to the spindle rails by nuts 4. The upper end of each stud is a head 5 on which is journaled an idler 7 which stands between, and whose diameter is equal to the space between, the adjoining parallel portions of the loops *d'* and *d²* of the belt (Fig. 7). Integral with the post 2 is a carrier 8 in the form of a plate. This carrier is apertured to receive the bearings 9' and 10' of spindles 9 and 10, the spindle 9 standing relatively outside of the adjoining stretch of the loop *d'* of the belt and the spindle 10 normally inside of the adjoining stretch of the loop *d²* of the belt. The plate may swing in a horizontal plane on stem 3 as an axis to bring both spindles into contact with the belt, (at that time supported as to both stretches against their pressure by the idler 7) whereupon they will rotate in the same direction, or out of contact therewith, it being normally held in the first-named position by a spiral spring 11 connecting it with a suitable part of the frame. Between the two stretches of the loops *d'* and *d²* of the belt the plate is formed with an aperture 12 into which the spindle 10 may be shifted, in which position, when the spindles are operatively engaged with the belt, they will rotate in reverse directions.

13 (Figs. 6 and 7) is a post secured in and projecting upwardly from the carrier 8 and penetrated by a vertical rod 14 splined in said post, the said rod carrying two horizontal arms 15. In these arms is journaled a threaded shaft 16 which has slight vertical movement, being cushioned by a spring 17 coiled about its lower end and interposed between a shoulder 18 of the rod and the lower arm 15; to the upper end of the threaded shaft 16 is secured a friction-wheel

19. Penetrated by the rod 14 is a carrier in the form of a plate 20 having an aperture 21 for the spindle 9, the said aperture being surrounded by a ring 22 on which is a thread guide 23 of the so-called "traveler" type. Coacting half nuts 24 are pivoted to the carrier 20 and normally held engaged with the threaded shaft 16 by a spring 25. By grasping the half nuts at the points indicated by the arrows in Fig. 9, the carrier 20 may be manually moved to any position on the threaded shaft 16. The structure including the rod 14, the rotary shaft journaled in the arms 15 and carrying the friction-wheel 19, and the carrier 20 is adapted to be reciprocated for the purpose of imparting the necessary traverse to the thread as it is wound around the spindle 9 as an axis, and, during such reciprocations, intermittent rotary impulses are imparted to the shaft 16 so that the carrier advances upwardly relatively to the spindle and rod 14 as the winding proceeds.

Describing, now the manner in which the traverse motion mentioned is accomplished, coinciding with each winding unit there are secured to opposite sides of the braces *c* pairs of brackets 26 in one of which in each pair is fulcrumed a curved lever 27 affording a bearing for a pinion 28 and a heart-cam 29 fixed to rotate together, the pinion 28 meshing with and being supported by a pinion 30 fixed on a shaft 31 which is journaled in the several uprights *a*. The rod 14 which penetrates the spindle rail *b* (the opening therefor in the spindle-rail being sufficiently large—Fig. 6—to allow said rod to swing with the carrier 8) carries at its lower end a roller 31' which rests upon the cam, the periphery of the roller being faceted so that, in view also of the eccentric mounting thereof, the rod will be elevated different distances in each series of revolutions of the cam requisite to effect one complete revolution of the roller, the object being to produce crossed windings of the yarn or thread.

Referring, now, to the manner in which the carrier 20 is elevated relatively to the spindle to advance the thread in the winding, 32 is a rotary horizontal shaft journaled in the upright *a* above the spindles and carrying the friction-wheels 33, each being adapted to contact with a friction-wheel 19 to impart a rotary impulse thereto whenever, in the up and down motion of the rod 14 and the parts it carries, the friction wheel 19 is brought in contact with the friction-wheel 33; it will be apparent that the cushioning of shaft 16 not only relieves the shock occurring each time the contact between the friction-wheels occurs, but renders such contact highly efficient to transmit the motion from the one to the other of said friction wheels. Each friction-wheel

33 may be secured to the shaft in such manner as to be adjustable toward and from the axis of rotation of friction-wheel 19 (in the vertical plane of which the shaft 32 is disposed) to vary the extent of movement 5 imparted to the threaded rod 16 each time the friction wheels engage each other.

There being two sets of spindle groups and their accessories above described, one at each side of the machine, as usual, there are 10 of course two shafts 31 and 32, as shown. Between the two shafts 32', journaled above the shaft 32, and on a stub-shaft 34 (Fig. 10) projecting from the end upright appearing 15 in Fig. 1 is journaled a rotary member comprising a pinion 35 and a bevel-gear 36, the rotary movement of said member being transmitted to the shafts 32' through transmission pinions 37 meshing with the pinion 35 and pinions 38 on said shafts. The drive-shaft *i* carries a pinion 39, and journaled in 20 the bracket *k* is a rotary member comprising a bevel-pinion 40, meshing with bevel gear 36, and a pinion 41; 42 is a transmission pinion meshing with pinions 39 and 41. By 25 interchanging the mountings for the pinion 37 and the member comprising 35 and 36 the mechanism to which they transmit power will be driven in such a way as properly to 30 coat with the spindles should they be rotated reversely by rotating shaft *i* reversely to the direction in which it rotates as shown in the drawings; upon such interchange, the pinion 42 and the member comprising 40 35 and 41 in Fig. 10 will be shifted to occupy the vacant slots shown in that figure.

The power is transmitted to the shafts 31 from shafts 32' (and incidentally from said shafts 32' to shafts 32) as follows: At the 40 end of the machine shown in Figs. 2 and 4 the shafts 32' carry pinions 43 with which mesh gears 44 adjustable in slots 45 concentric with the shafts 32 on which are fixed the pinions 46 which mesh with pinions 47 45 fixed to rotate with the pinions 44. Each pinion 46 carries a sprocket wheel 48 around which and a sprocket wheel 49 carried by a pinion 50 meshing with a pinion 51 on the shaft 31 extends the sprocket chain 52; to 50 vary the speed of rotation of each shaft 31 relatively to shaft 32 a pinion 50 of different size may be employed, 53 being a slot in which the mounting for the pinion is arranged allowing its proper engagement with 55 the pinion 51 whatever its diameter.

54 are horizontal arms each secured to a rail 54' above a spindle 9 and in a slot 55 in each arm is arranged to slide a vertically movable bracket 56 which normally stands 60 in the position shown in Fig. 6 but which, when moved upwardly, is caused by a spring 57 to be caught by its shoulder 58 and hang suspended from the rail. By an adjustable slot and pin connection 59 the lower end of 65 this bracket is connected by a pitman 60

with one arm of a dog 61 pivoted in the spindle-rail, the other arm of said dog being adapted to shift the carrier 8 against the tension of its spring 11 (Figs. 6 and 7); 62 is a link connecting the end of lever 27 with 70 the first-named arm of the dog. In the bracket 56 is journaled a peripherally grooved thread-advancing wheel 63 which, in the normal position of the bracket, peripherally engages a friction wheel 64 on 75 the shaft 32'. It will be apparent that when the bracket 56 is elevated out of its normal position it disestablishes contact between the wheels 54 and 63, causes the dog to shift the carrier 8 to disestablish contact between 80 the spindles 9 and 10 and the belt *d* and disestablishes the connection between pinions 28 and 30, so that the advancing of the thread by the wheel 63, the rotation of the spindles and the traverse motion are all 85 stopped simultaneously. Side by side with the friction wheel 64 is a ratchet 65 with which engages the lower end of a dog 66 when said dog is caused to move out of its normal position, *i.e.*, where its upper weight- 90 end rests against a stop 67 on the bracket 56 in which the dog is pivoted. The dog is moved out of its normal position by one of a group of fallers 68 each normally held in the position shown in Fig. 6 by the thread, 95 which is passed around the guides 69 on the bracket 56 and also around the upper or longer arm of the faller. If the thread breaks, the faller, being released, moves against the dog and throws it into the path 100 of the ratchet whereby the bracket 56 is elevated and latches itself to the rail 55, stopping the different mechanisms controlled thereby, as described.

In doubling, twisting and quilling, the 105 threads are taken from supply bobbins 70 arranged on skewers in substantially radial relation to a horizontal bar 71 over which and a broad curved blade 72 laterally and rotatably adjustable on said bar the threads 110 are passed, from whence they extend around the guides 69 and the faller, then around the peripherally grooved advancing wheel 63 (preferably extending also through a guide 73 insuring their being retained on the advancing wheel) and then through traveler 23 to the spindle 9. The thread is 115 shown as thus described in broken lines, Fig. 3. By rotatably adjusting blade 72 on the bar 71 the tension may be varied, as will be 120 obvious.

In quilling, without doubling or twisting, a supply spool is placed on the spindle 10 and the thread is extended through the 125 guide 74, around guides 69, engaged with a faller and passed around the advancing wheel, and thence through traveler 23 to the spindle 9, the two spindles rotating in reverse directions because at that time the spindle 10 occupies the aperture 12 in the 130

- carrier. The thread is shown as thus described in Fig. 6 in broken lines. If a compound twist is desired, the spindle 10 occupies the position shown therefor in Fig. 7, 5 where both spindles rotate in the same direction. In quilling with a single twist, the thread is taken from one of the spools 70 and supplied to the rotating spindle 9 the same as in doubling, twisting and quilling.
- 10 The wheel 63 being directly over the receiving spindle 9 it is available to advance the thread in any of the foregoing operations. By changing the ratio of the speeds of the rotary receiving spindles and the 15 traverse mechanisms the pitch of the windings may be varied; and by changing the ratio of the speed of the spindles relatively to the extent (or frequency) of contact of friction wheels 19 and 33, the diameter of 20 the wound package may be varied.

It will be observed on reference to the drawings that the nearest point relatively to the traveler 23 at which the thread is guided is sufficiently away from as well as 25 substantially alined with the spindle so that the thread balloons and thus creates a resistance to the advance of the thread which produces a nicely adjusted or natural tension, sufficient to keep the thread under 30 proper control at all times without tending to produce undue breakage. The "hardness" (compactness) of the wound package may be varied by varying the weight of the traveler.

35 Having thus fully described my invention, what I claim as new and desire to secure by Letters Patent is:—

1. In combination, with a supporting structure, a spindle driving belt, means for 40 driving the belt, parallel spindles arranged on opposite sides of the belt, and means for supporting and moving the spindles into and out of simultaneous contact with the belt including a carrier carrying both spindles and pivoted to move on an axis parallel with the spindles, substantially as described.

2. In combination, with a supporting structure, a continuous spindle-driving belt having two reversely advancing stretches 50 thereof arranged substantially parallel with each other, means for driving the belt, parallel spindles arranged on relatively opposite sides of and respectively engageable with said stretches of the belt, and means for supporting and moving the spindles into and 55 out of simultaneous contact with the belt including a carrier carrying both spindles and pivoted to move on an axis parallel with the spindles, substantially as described.

60 3. In combination, with a supporting structure, a continuous spindle-driving belt having two reversely advancing stretches thereof arranged substantially parallel with each other, means for driving the belt, an 65 idler journaled between and spacing said

stretches of the belt, parallel spindles between which said stretches of the belt extend, said spindles being parallel with the axis of the idler, and means for supporting and moving the spindles into and out of 70 simultaneous contact with the belt including a carrier carrying both spindles and pivotally movable around the axis of the idler, substantially as described.

4. In combination, with the frame, a rotary driving member, a reciprocating structure situated below and movable toward and from said member, means for reciprocating said structure situated below the same, a spindle-member extending substantially parallel with the path of movement of said structure, a thread-guide member, said thread-guide and spindle-members being co-active in winding the thread and one being rotary around the spindle axis, and means 80 for supporting the thread-guide member in said structure and effecting advancement thereof parallel with the spindle axis comprising a rotary driven member journaled in said structure and engageable with the 85 driving member, substantially as described.

5. In combination, with the frame, a rotary driving member, a reciprocating structure movable toward and from said member, means for reciprocating said structure, a spindle-member extending substantially parallel with the path of movement of said structure, a thread-guide member, said thread-guide and spindle-members being co-active in winding the thread and one being 90 rotary around the spindle axis, and means for supporting the thread-guide member in said structure and effecting advancement thereof parallel with the spindle axis comprising a rotary driven member journaled in said structure and engageable with the 95 driving member, substantially as described.

6. In combination, with the frame, a spindle member, a thread-guide-member, one of 100 said members being rotary around the axis of the spindle member, and means for effecting traverse of one of said members including a supporting structure for the traversed member, a rotary driving member journaled 105 in the frame, a rotary cam-including driven member normally resting upon the driving member, said structure being supported by the cam of said driven member, and a lever fulcrumed in the frame eccentrically of the 110 axis of the driving member and carrying the driven member, substantially as described.

7. In combination, with a supporting structure, substantially parallel receiving and supply spindles having their free ends 115 projecting in substantially the same direction, a belt having reversely moving stretches, said stretches being respectively engaged by the spindles on relatively opposite sides thereof whereby to rotate the spin- 120 125 130 135

dles in the same direction and obtain a compound twist in the thread, a common carrier for said spindles pivotally movable to move the spindles into and out of simultaneous contact with the belt, and means for conducting the thread from the supply to the receiving spindle, substantially as described.

In testimony whereof I affix my signature in presence of two witnesses.

FRANCIS SEYMOUR.
